DIMMITT ROSS LOVEJOY, OF NEW YORK, N. Y., ASSIGNOR TO LOVEJOY DEVELOPMENT CORPORATION, OF NEW YORK, N. Y., A CORPORATION OF NEW YORK

INDICATOR FOR RADIO DEVICES

Application filed November 28, 1925. Serial No. 71,973.

My invention relates in general to means for actuating the rotary elements of radio control devices, such as condensers, inductances, rheostats, and the like which are ordinarily mounted on the panel of the set.

The so-called tuning dial in the radio art has, under modern development, come to be a recognized article of manufacture which can be purchased on the market and applied 10 to the projecting shaft of the control device it is intended to actuate. At the present time, such dials are mostly employed on the condenser shafts and are provided with a scale or pointer to indicate the extent of the rotary 15 movement of the condenser rotor by which the tuning of a circuit is adjusted. In the present condition of radio transmitting stations having wave length assignments bordering closely on each other, the necessity for 20 accurate tuning has become acute and many of the actuating dials are provided with so-called "vernier actuation" in order to obtain closer adjustment of the condenser rotor. In most of these an exact and definite proportion 25 of the movement of the main dial with relation to the "vernier actuation" is not absolutely insured, on account of the use of uncertain frictional drive, and even where the drive may be more or less constant and fixed, 30 such as by gearing, back-lash may still occur to render the problem of repeating a very exact setting of the condenser over and over again, a very difficult one. Whether due to 35 this mechanical difficulty or not, the fact remains that in none of the forms heretofore produced has there been any possibility of, or provision for, observing with micrometric sharpness the exact position of the condenser setting and recording the same so that the 40 same position or setting may be repeated without difficulty.

An object of the present invention is primarily to provide a construction for actuating and indicating with great accuracy the adjustment of the condenser or other radio control device, so that the precise setting may be recorded and repeated without difficulty.

An example of the principle of construction and operation in which I attain the advantages of the present invention will be de-

scribed, in connection with its use upon a rotary condenser, as illustrated in the accompanying drawing.

In said drawing, Figure 1 is a vertical section, in an axial direction, showing a condenser mounted upon a panel and having on its shaft an embodiment of the indicating and actuating mechanism forming the subject matter of the invention. 55

Figure 2 is a face view of the indicating and actuating mechanism shown in Figure 1, with a part of the housing broken away. 60

Figure 3 is a detail face view of the proportionate drive connection in the form of gear and pinion, as seen from the rear on the line 3-3 of Figure 1. 65

Figure 4 is a detail view, as seen from the rear on line 4-4 of Figure 1, illustrating the construction by which the torque reaction on the pinion is taken up. 70

Referring now more specifically to said drawing, 1 indicates the condenser shaft having fixed thereon, by soldering or otherwise, the set of movable plates 2, which are rotatable between the fixed plates 3 of the condenser. 75 The construction of the condenser is not in itself a feature of the present invention and I have illustrated only enough to make clear the application of the invention. The condenser is mounted in any approved or ordinary manner upon the back of the panel 4, with the rotor shaft 1 projecting forwardly thru a perforation in the panel.

The invention contemplates in a general way, a plurality of rotary members or elements which are interconnected for proportionate movement and have related to them scale or indicating devices by which the proportionate movement of the respective rotary elements may be graduated to extreme 90 fineness. For all ordinary purposes two of such rotary elements will be sufficient and the scale applied to one may be marked off in units of complete turns of the other, whereas the scale applied to the other may be marked 95 off in degrees or any suitable number of subdivisions one complete revolution.

The example illustrated embodies two of such rotary members, one of which may preferably be mounted upon the rotary shaft 1 of 100

the condenser or other analogous device and move in fixed relation thereto. Such a rotary element is illustrated for example at 5 as mounted upon shouldered hub 6 which is secured upon the shaft 1 by set screws or the like. The rotary element 5 is backed by the gear wheel 7 which may be secured on the rear of the hub 6 by screws passing thru perforations therein and thru the rotary element 5 into the shoulder of the hub 6. It will be observed that the rotary element 5 is in the form of a disk which is thus effectively clamped in fixed position between the gear 7 and the shoulder of the hub 6 so that these three parts move in unison with the condenser shaft 1 and the rotary plates 2. A scale may be conveniently applied to the face of disk 5 near its outer edge, to be read thru a sight opening 9 in the housing 8 in conjunction with a stationary reference pointer 10, as clearly shown in Figures 1 and 2. The housing 8 is fitted over the hub 6, and may be held in place thereon by a cap 6', against the front face of the shoulder of the hub. The hub however, is free to turn in the perforation thru which it passes in the front wall of the housing 8.

The second rotary element, in the form of a disk 11, is fixed on the rear face of a turning knob 12 which is journaled on a tubular post 13 inserted in a perforation in the lower portion of the housing 8 and secured to the housing wall by means of the nut 14 which is threaded on to the inner end of the post. A floating shaft 15 has its forward end firmly fitted into a socket or recess axially disposed within the knob 12 and is held therein by means of set screws 16, or in any other suitable manner. This floating shaft 15 passes rearwardly thru the tubular post 13 and terminates just short of the panel 4 where it carries a spur pinion 17 which is fixed on the floating end of the shaft and held firmly in mesh with the teeth of the gear 7 above described by suitable means such as a resilient wire 18 having its bent ends 19 fitted into radial perforations or recesses formed in the rim flange of housing 8, as clearly shown in Figure 3. This spring presses resiliently against the projecting rear end of floating shaft 15 and thus urges the pinion 17 toward the gear 7. With this construction, I prefer to employ a special provision for taking up the torque reaction of the spur gear 17, such as illustrated for example in Figures 1 and 4. This feature comprises the slotted end wall or disk 20 at the rear of tubular post 13 thru which the shaft 15 passes. The slot in this wall or disk 20 is disposed radially of the gear 7 so that the resilient wire 18 is not opposed in its function of urging the spur gear toward the gear 7, but any non-radial movement or swinging of the inner end of floating shaft 15 is effectively prevented. Shaft 15 is of such a character and of physical dimensions as to yield under the influence of the resilient wire 18 and hence the necessity of resisting the torque reaction by some special construction other than the stiffness or the rigidity of the shaft itself.

The mounting of the dials and housing upon the condenser shaft 1 in the manner described requires no particular provision for further supporting the parts in position on the front of the panel, but it is of course, necessary to prevent the housing from turning or swinging. This action may conveniently be prevented by passing a screw or bolt 22 thru the housing 8 and into a perforation or recess in the panel 4. In order to employ a dial 5 of greater diameter than the gear 7 it is, of course, necessary to recess the dial or disk 5 on an arc corresponding with the position of the spur gear 17 so that the shaft 15 and spur gear 17 may have access to the gear 7 without interrupting the free path of the disk 5. Thus I have illustrated the disk as being perforated at 21, which is clearly seen in Figures 1, 2 and 3.

The construction shown and described provides a very accurate proportionate movement of the two rotary members so that a micrometric scale may be applied to the respective parts and relied upon to enable the operator to record and reproduce a critically exact setting of the control device. The disk 5 is here shown by way of example as being calibrated in units, each of which represents one complete turn of the disk 11, whereas the disk 11 may be calibrated in any fractional sub-division to represent fractions of one turn. Thus by sub-dividing the scale of disk 11 into one hundred equal divisions and sub-dividing one half of the circumference of disk 5 into ten equal divisions each representing one complete turn of the disk 11, the exact setting can always be read in three figures. For example, if the dial of disk 5 indicates between the division point 3 and division point 4 with reference to the pointer 10, and the scale of disk 11 reads 7 divisions from a fixed reference line on the face of the housing, the condenser setting 307 will be very easily read and recorded and may be reliably reproduced at any time. Without the proportionate relationship between the motion of disk 5 and the motion of disk 11 being accurately maintained, or even with a reliable proportionate movement but with no way of reading accurately the position of disk 11, the recording of the control setting and its subsequent re-setting to the precise position with a nice degree of accuracy would be unattainable.

I claim:

1. A micrometric indicator for rotary radio control devices, comprising in combination a pair of rotary elements, one of which has means for operatively connecting

it with the rotor of the radio control device, to be actuated, a gear and a pinion mounted on the respective rotary elements, means for resiliently urging said pinion 5 radially toward said gear, and a guide way for preventing the deviation of said pinion from such radial path.

2. Apparatus of the character described comprising in combination a gear, a tubular 10 post having a guide slot at its inner end, directed toward said gear, a turning knob journaled on said tubular post, a shaft fixedly secured at its forward end in said turning knob and extending rearwardly thru said 15 tubular post and the slotted rear end thereof, a pinion fixed on the free inner end of said shaft beyond said tubular post, and meshing with said gear and means for resiliently urging the free end of said shaft toward 20 said gear in the direction of said guide slot.
